UNITED STATES PATENT OFFICE.

OLIVER W. KETCHUM, OF BALTIMORE, MARYLAND, ASSIGNOR, BY DIRECT AND MESNE ASSIGNMENTS, TO THE RAYMOND BUTTON COMPANY, OF SAME PLACE.

METALLIC BUTTON.

SPECIFICATION forming part of Letters Patent No. 634,173, dated October 3, 1899.

Application filed March 24, 1898. Renewed April 26, 1898. Serial No. 678,908. (No model.)

To all whom it may concern:

Be it known that I, OLIVER W. KETCHUM, a subject of the Queen of Great Britain, residing at Baltimore, in the State of Maryland, 5 have invented a certain new and useful Improvement in Metallic Buttons, of which the following is a specification, reference being had to the accompanying drawings.

This invention is an improvement on that 10 style of button shown in my Patent No. 555,868, intended to make the same easier to apply to a garment; and to this end the invention consists in the peculiar construction and arrangement of parts hereinafter more 15 particularly described and then definitely claimed at the end hereof.

In the accompanying drawings, Figure 1 is 20 a plan of a button constructed according to my improvement. Fig. 2 is a bottom plan. Fig. 3 is a cross-section with the fastening in place. Fig. 4 is a similar view at right angles to that in Fig. 3. Fig. 5 is a plan of a button with a cap of different form. Fig. 6 is an enlarged detail perspective of the button 25 represented in Figs. 1, 2, 3, and 4, partly broken away. Fig. 7 is a detail of the fastener.

Referring now to the details of the drawings by figures, 1 represents the body of the 30 button, provided with a neck 2, from which depends a cross-bar or bridge 3. In the neck is set a cap 4, having a semicylindrical projection 5, forming a hollow recess 6. The axis of the semicircular projection should be 35 set substantially parallel with that of the cross-bar or bridge 3, in which position it is held by the friction between the edges of the cap and the inner surface of the neck, the cap being forced into the neck under great 40 pressure.

The fastener may be of any approved form, 45 preferably such as shown in my aforesaid patent or as in Fig. 7, and having a disk 7 and prongs 8, which latter are each set off to one side of a central line, so that when turned inward they will be apt to pass each other.

In some cases I make the cap with an indented ridge 9, (see Fig. 5,) set at an angle to the bridge below, as in my aforesaid patent, in order to make sure that the points of 50 the fastener will not come in contact with each other, as the ridge will prevent this; but either form of cap may be used.

In applying this button to a garment the 55 prongs of the fastener are forced through the cloth into the apertures 10 on each side of the bridge, and as they strike the wall of the recess 6 of the projection they coil over and pass each other, as shown in Figs. 3 and 4.

The fastener may be forced into its place 60 by any convenient means; but I prefer to do it by special machinery which need not be fully described here, as it forms no part of the present invention; but it may be said that part of it consists of a guide for the but- 65 tons, having a groove in which the pendent bridge 3 slides, so that the button is always held in such a manner that the prongs will be sure to enter the holes 10. This pendent bridge is an important part of my invention, 70 for if the holes 10 were not in the proper position the prongs might strike the bridge and either break or damage the bridge or button. The pendent bridge may also serve as a guide 75 in setting the cap in place in its proper relative position to said bridge when the button is being manufactured.

I deem the semicylindrical recess an important feature of my invention for the reason 80 that by its use I am enabled to more certainly prevent the points of the prongs from coming in contact with each other than when the cap is semispherical, as in my aforesaid patent, inasmuch as there is a tendency in the semispherical cap to crowd the points of the prongs 85 toward each other, which is avoided by the use of the semicylindrical recess, so that the ridge 9 may be dispensed with, although the same may be used, if preferred.

What I claim as new is—

1. A button having a body 1, a neck 2, a cap set therein having a semicylindrical re-

90

cess, and a bridge at the bottom of the neck, substantially parallel with the axis of said recess as set forth.

2. A button-body having a semicylindrical recess and a bridge set centrally under and substantially parallel with the axis of said recess as set forth.

3. As an improved article of manufacture, a button comprising a body 1, having a neck 2, a pendent bridge 3, and a cap provided

with a semicylindrical recess having its axis parallel with said bridge, all substantially as described and shown.

In testimony whereof I affix my signature, in the presence of two witnesses, this 23d day ¹⁵ of March, 1896.

OLIVER W. KETCHUM.
